US00D980438S

(12) **United States Design Patent** (10) **Patent No.:** **US D980,438 S**
(45) **Date of Patent:** **** Mar. 7, 2023**

(54) **CAVITATION MACHINE**

(71) Applicant: **Shenzhen Qinjia Technology Co., Ltd.**, Shenzhen (CN)

(72) Inventor: **Jaimei Yuan**, Shenzhen (CN)

(73) Assignee: **Shenzhen Qinjia Technology Co., Ltd.**, Shenzhen (CN)

(**) Term: **15 Years**

(21) Appl. No.: **29/847,713**

(22) Filed: **Jul. 27, 2022**

(51) **LOC (14) Cl.** **24-01**
(52) **U.S. Cl.**

USPC **D24/200**; D24/215

(57) **CLAIM**

The ornamental design for a cavitation machine, as shown and described.

DESCRIPTION

FIG. 1 is a front perspective view of a cavitation machine, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the cavitation machine, which form no part of the claimed design.

1 Claim, 7 Drawing Sheets
